ATTORNEY

UNITED STATES PATENT OFFICE.

CHARLES W. DAKE, OF CHICAGO, ILLINOIS.

ELECTRIC LIGHT.

Application filed February 23, 1923. Serial No. 620,561.

To all whom it may concern:

Be it known that I, CHARLES W. DAKE, a citizen of the United States, residing at Chicago, in the county of Cook and State of Illinois, have invented a certain new and useful Improvement in Electric Lights, of which the following is a specification.

My invention relates to an improvement in electric lights for use especially in connection with locomotive electric head lights and similar purposes where an incandescent electric light is used as the source for an illuminating or search light ray associated with a parabolic reflector.

15 It is, of course, a known fact that the best place for such a source of light is at the focal center of the reflector, and that the farther away the source gets from the focal center the less satisfactory becomes the light.

It is impossible to have all of the light at the focal center, and I have discovered that the next best place is to have the light filament strung along the central axis of the reflector, passing through the focal point. Next to this the best place for the light is in a plane perpendicular to this axis and passing through the focal point.

Especially in connection with locomotive electric headlights where the voltage is comparatively low, it is necessary, in order to get a lamp which will comply with the necessary service conditions, to have a filament which is of comparatively great length, and in the past it has been the practice to 25 provide the filament arranged in a grid in a plane perpendicular to the focal axis.

I propose to provide in my bulb for incandescent light a comparatively large portion of the filament located on or immediately 40 adjacent to and surrounding this focal axis and projecting both in front of and behind the focal point. I propose to locate the balance of the filament in the plane perpendicular to this axis and passing

45 through the focal point. Experience shows that this arrangement results in a maximum of illumination and prevents the presence of any dark spots or dark areas in the beam of light.

50 My invention is illustrated more or less diagrammatically in the accompanying drawings, wherein—

Figure 1 is a perspective view of an elec-

tric light globe showing the filament in place;

Figure 2 is a detailed side elevation of the filament and the supporting anchorages;

Figure 3 is a plan view of the bulb.

Like parts are indicated by like characters.

A is the glass bulb or globe of the conventional type of incandescent electric light. It is provided with a screw-threaded base A¹ adapted to be screw-threaded into a socket and cemented as at A². Projecting upwardly from the base is a support A³, of glass or other suitable material, in which are imbedded or inclosed conductors A⁴ and A⁵. This support terminates at its upper end in a base A⁶ from which project upwardly the three supporting arms A⁷, A⁸, A⁹, and a holding hook A¹⁰.

Passing through the wall of the base A³ and associated with the conductor A⁴ is a conductor hook B, which is curved away from the filament and terminates on the focal line, where it supports the outward end of a coiled filament B¹. This coiled filament extends inwardly along the focal line, passing through the focal point, and is held by the hook A¹⁰ at a point behind the focal plane. An inclined stretch or branch of this filament extends from the hook A¹⁰ to the support A⁹, which terminates in the focal plane. From here the filament extends to the hooks A⁸, A⁷, back to a point adjacent the hook A⁹, where it is carried by the conductor and support B² which passes in through the wall of the member A³ and terminates at the conductor A⁵, thus giving an arrangement by which the coiled filament is supported in comparatively short coiled sections insulated except at the two ends where it is mounted on the conductors, and anchored and positioned partially in the focal plane and partially on the focal line.

The filament itself is preferably formed of a single closely coiled spiral wire of the usual type. This coil is so fine and so close that for all practical purposes it may be treated and considered as a single straight wire, and while geometrically, of course, the size of the coiled wire portion is large in fact, nevertheless, being placed right on the focal line as it is, it may for all practical

purposes be considered as an incandescent filament on the focal line. The same comment applies to that part of the filament located in a plane perpendicular to the focal line.

I claim:

1. In an electric light globe, a base, a support projecting upwardly therefrom within said globe, a longitudinal filament section upwardly projecting from said base, a holding hook adapted to hold the outer end of said longitudinal section, a plurality of transverse filament sections located in a single plane intermediate the ends of and perpendicular to the longitudinal section and surrounding it, and a plurality of hooks upwardly and outwardly projecting from said support, adapted to support said transverse sections.
2. In an electric light globe, a base, a support projecting upwardly therefrom within said globe, a longitudinal filament section upwardly projecting from said base, a holding hook adapted to hold the outer end of said longitudinal section, a plurality of transverse filament sections located in a single plane intermediate the ends of and perpendicular to the longitudinal section and surrounding it, and a plurality of hooks upwardly and outwardly projecting from said support, adapted to support said transverse sections, said first mentioned hold-

ing hook being outwardly bowed to avoid said transverse filament sections, and inwardly curved above them to a point in line 3. with said support.

3. In an electric light, a luminous filament having a longitudinal section lying substantially along the axis of the lamp, and a plurality of transverse sections located in a single plane intermediate the ends of and perpendicular to the longitudinal section.

4. In an electric light, a luminous filament having a longitudinal section lying substantially along the axis of the lamp, and a plurality of transverse sections located in a single plane intermediate the ends of and perpendicular to the longitudinal section, and substantially surrounding it.

5. In an electric light having a glass stem, a luminous filament upwardly projecting from said stem and lying substantially along the axis of the lamp, a plurality of transverse sections located in a single plane intermediate the ends of and perpendicular to the longitudinal section, and supporting hooks upwardly and outwardly extending from said stem and adapted to support and position said sections.

Signed at Chicago, county of Cook, and State of Illinois, this 19th day of February, 1923.

CHARLES W. DAKE.
